MEANS FOR MANUFACTURING FOOTWEAR

David Gordon Gash, Balaclava, Victoria,
AustraliaApplication April 23, 1936, Serial No. 75,997
In Australia April 26, 1935

2 Claims. (Cl. 18—42)

This invention has reference to a method of and means for manufacturing footwear and has been devised to provide footwear which is moulded in lieu of being constructed in various parts 5 to form the completed shape.

It has been the accepted practice in the manufacture of footwear particularly when moulding rubber or like resilient shoes or boots to form the same in various sections which are united by 10 cementing together both the parts to be conjoined and the lining of canvas or the like which necessitated costly and tedious operations while in the finished product the parts had a tendency to disunite more particularly the sole from the 15 upper canvas.

The main object of the present invention is to provide a method of manufacturing footwear particularly rubber boots and shoes in one complete unitary structure and wherein the above 20 disadvantages and defects are obviated, the finished article being of the necessary resiliency and having the quality and durability to withstand normal use without becoming misshapen, which is a detrimental feature of leather footwear, while 25 the normal shape of the shoe or boot conforms to the shape of the foot when removed therefrom.

With the above object in view the present invention consists in moulding footwear in one complete structure and wherein the last or core 30 which is of a standard shape is firstly coated with uncured rubber after which the sole and heel portion is shaped on the last by pressure whereby the form may be cooked in a vulcanizer with the resultant moulded product being a boot or shoe 35 formed in one complete unit of the desired shape and size.

An important feature embodied in my invention is that during the application of the uncured rubber to the last or core it may be suitably coloured and shaped to a desired configuration, while the sole and heel may be constructed 40 of rubber having less resiliency or elasticity than the material employed for the upper.

Another important feature embodied in my 45 invention is the provision of means for moulding a shoe or boot by the method described and by the employment of said means moulding the said footwear in one complete structure of a desired shape the means preferably comprising a mould 50 constructed in two correspondingly shaped sections between which may seat a last or core of selected size while a selected pressure plate is associated with said sections to seat therebetween and over the base of the last or core where- 55 by after the rubber or material is coated on said

last the closure of the sections under pressure effects a positive conforming of the unvulcanized rubber to the shape of the last and selected pressure sole and heel plate to bring the moulded shoe or boot to the condition of being cooked in 5 a vulcanizer or other practical apparatus.

A further important feature embodied in the invention is that the soles and heels are composed of a rubber having a substantially harder composition than that of the upper while the sole 10 may have formed thereon a tread of desired configuration.

The invention will be hereinafter more particularly described with reference to the accompanying drawing showing a mould for carrying 15 out the method according to the invention and in which:—

Figure 1 is a plan view of one section of the mould having the core and sole pressure plate positioned therein.

Figure 2 is a plan view of the co-acting section 20 of the mould.

Figure 3 is a sectional elevation of the assembled mould sections with the core and sole pressure plate in position.

Figure 4 is an elevation of the core or last of the mould.

Figure 5 is a sectional elevation through line 25 5—5 of Figure 4.

Figure 6 is an elevation of the sole and heel pressure plate.

Figure 7 is a sectional elevation through line 30 7—7 of Figure 6.

According to one form of carrying my invention into practical effect with the method previously described I provide a mould comprising two co-acting sections 10 each section being hollowed to form a recess 11 therein adapted to receive with a predetermined clearance one side or portion of a correspondingly shaped last or core 40 12 which conforms to a standard shape. Formed adjacent the base of the recess 11 in each section 10 is an extended recess 13 adapted to receive a sole and heel pressure plate 14 this latter recess 13 being slightly deeper than the recess 45 11 shaped to receive the last 12 for the purpose of providing a welt on the moulded shoe or boot.

The back of the pressure plate 14 for forming the sole and heel is formed with oppositely disposed tapered cam surfaces 15 extending outwardly from each edge and converging in the approximate centre of said plate 14, correspondingly tapered cam surfaces 16 being provided on the adjacent edges of the moulding sections 10. Such tapered surfaces 15 and 16 are for the pur- 55

pose of facilitating the entry of the pressure plate 14 when the last 12 is in position and is coated with uncured rubber 17 the said pressure plate 14 being forced in a direction parallel to the interface between the sections 10 of the mould 5 are assembled.

In order to prevent the last 12 from being forced out of position when the sections 10 of the mould are being assembled I provide one or more keyways or grooves 18 on the upper or positioning portion of the last 12 which keyways 18 are adapted to engage with projecting keys or ridges 19 formed on the mould section 10. The 15 keyways 18 and keys 19 are preferably made with interfitting inclined cam faces so as to guide the core into its proper position when the mould sections are moved together to close the mould. The core is then held firmly in its proper position 20 by interengagement of the cam faces of the keys and keyways until the mould is opened.

Conveniently positioned on the adjacent faces of the co-acting sections 10 of the mould I provide small channels 20 which extend to the edge 25 of the mould sections 10 these channels 20 being for the purpose of permitting the discharge of excess material that is forced from the mould during operation.

A separate mould may be made for each last 30 12 with pressure plate 14 but it is preferable to incorporate a pair of right and left lasts 12 and pressure plates 14 in the one section 10 as illustrated in the accompanying drawing.

In building up a last 12 the said last 12 is removed from divided sections 10 of the mould and coated with a layer of uncured rubber 17 of predetermined thickness; any portion of the coating of rubber may be suitably covered or have a pattern imparted thereto, a coating of rubber 40 of harder composition if desired being applied to the sole of the last 12 for the purpose of forming the sole and heel of the boot or shoe. The last 12 is then placed in position in one of the correspondingly shaped recesses 11 formed on each internal side of the co-acting sections 10 of the mould.

The pressure plate 14 is then inserted into the mould section 10 carrying the last 12, in the recess 13 directly below the bottom of the last 12 50 but owing to the thickness of the uncured rubber 17 this pressure plate 14 is prevented from being correctly positioned without pressure being applied thereto, but due to the taper 16 on the back face of the pressure plate 14 the entry of said plate 14 into the mould section 10 is made possible. The interaction between the inclined faces 16 of the mould on the inclined faces 15 on the pressure plate forces the pressure plate toward the core member 12 as the mould sections move 60 toward each other until the pressure plate occupies its correct position within the cavity of the mould.

The surface of the heel and sole plate 14 adjacent the bottom of the last 12 may be of desired formation according to requirements and may have formed thereon projections 21 or the like for imparting a desired tread on the sole of the finished product.

Should it be desired the heel section 22 of uncured rubber 17 may be stamped out and placed adjacent the heel of the last 12 prior to the insertion of the heel pressure plate 14 and reinforcing fabric (not shown) is incorporated with the uncured rubber 17 forming the upper of the shoe 75 in order to prevent fracture of the rubber at a

position where eyelets (not shown) are inserted after the product has been vulcanized.

The effective surface or recess 11 of the mould section 10 may be provided with projections or indentations 23 in order to impart to the exterior 5 of the shoe a desired pattern or configuration and similarly the last 12 may be provided with indentations 24 on the back of the heel in order that the interior of the moulded product may have gripping means formed thereon such as a 10 plurality of spaced projections.

With the last 12 having the coating of uncured rubber 17 of suitable composition and uncured hardened sole and heel applied thereto in the operative position and the pressure plate 14 inserted into the section 10 of the mould, the co-acting section 10 of the mould is then placed in position and pressure applied thereto thereby forcing the sole and heel pressure plate 14 downwardly and at the same time inwardly against 20 the sole of the last 12. While the co-acting sections 10 of the mould are held together under pressure suitable fastening means associated with said sections 10 are brought into operation, the said fastening means preferably comprising a pivotal bolt 25 adapted to engage projecting lugs 26 on the opposite section 10 of the mould. The mould is then placed in a suitable vulcanizer (not shown) for a period sufficient to cook the uncured rubber 17 after which the mould is removed and opened, and the core or last 12 removed from the vulcanized rubber shoe or boot as the case may be.

The shoe is then dressed and prepared to remove any excess material formed at the joint 35 of the mould sections 10 and suitable eyelets (not shown) incorporated in the front of the shoe for lacing purposes, the tongue (not shown) of the shoe being inserted and fixed to the upper by the lower eyelets.

In order to obtain a predetermined thickness of the sole of the shoe varying sized pressure sole plates 14 are provided for the purpose. Dowel pins 27 and co-acting dowel openings 28 are also provided on the mould sections 10 to ensure correct alignment.

It will be understood that the product obtained by the method herein described has the natural appearance of a standard shaped last and from appearance is identical with a leather shoe having a welted sole thereon.

What I claim as my invention and desire to secure by Letters Patent is:—

1. A mould for forming one-piece rubber shoes, which comprises a pair of mould sections having recesses therein cooperating to form a cavity when the mould is closed and having core positioning portions, and a unitary core member having a core portion in the shape of a shoe last adapted to be spaced from both mould sections when in position in the closed mould and a positioning portion integral with said core portion, said core-positioning portions of both the core member and the mould sections comprising interfitting ridges and grooves with inclined cam faces adapted to move said core portion into proper position relative to the mould sections when the mould sections are moved together to close the mould.

2. A mould for forming one-piece rubber shoes, which comprises a pair of mould sections having recesses therein cooperating to form a cavity when the mould is closed and having core positioning portions, a unitary core member having a core portion in the shape of a shoe last adapted to be spaced from both mould sections when in

position in the closed mould and a positioning portion integral with said core portion, said core-positioning portions of both the core member and the mould sections comprising interfitting ridges and grooves with inclined cam faces adapted to move said core portion into proper position relative to the mould sections when the mould sec-

tions are moved together to close the mould, and a sole pressure plate in said cavity opposite the bottom of said core, said sole pressure plate and mould sections having coacting cam faces to force said plate toward said core when the mould sections are moved together to close the mould. 5

DAVID GORDON GASH.
